UNITED STATES PATENT OFFICE.

HENRY W. BOLLINGER, OF ALTOONA, PENNSYLVANIA.

HEADLIGHT-ADJUSTER FOR AUTOMOBILES.

1,133,224.

Specification of Letters Patent.

Patented Mar. 23, 1915.

Application filed May 6, 1914. Serial No. 836,690.

To all whom it may concern:

Be it known that I, HENRY W. BOLLINGER, a citizen of the United States, residing at Altoona, in the county of Blair and State 5 of Pennsylvania, have invented certain new and useful Improvements in Headlight-Adjusters for Automobiles, of which the following is a specification.

This invention relates to automobiles, and 10 has for its primary object improved means for actuating pivotally mounted headlights, independent of each other, through the medium of the steering mechanism of the car, yet separate and apart from the same. 15 Another object of this device is to provide an improved headlight mechanism whereby, when the car to which the lights are attached is rounding a curve, the light on the inside of the curve will throw its rays 20 in a direction parallel to the plane of the front wheels, while the lamp on the outer side of the curve will throw its rays parallel to the plane of the car.

A further object of this device is to provide a simple pivotal lamp bracket adapted 25 to be operated through the medium of the steering gear, while the pivotal brackets are entirely disconnected from each other in such manner that when the car is operating 30 on a tangent the lamps will each throw its rays parallel to the plane of the car, and not be affected by the irregularities of line of movement over the road, thus tending in a very practical way to obtain a steady light 35 in straight-ahead travel as well as to illuminate the inside and the outside of the curve when the car leaves the tangent.

A still further object of this device is to provide a mechanism that is extremely simple and which also reduces the rattling noise 40 to a minimum, and at the same time provides a positive and reliable device which is of a pleasing mechanical appearance on the car.

With these and many other objects in view, which will be more readily apparent as the nature of the invention is better understood, the same consists of the novel construction, combination and arrangement 50 of parts as will be hereinafter fully pointed out, illustrated and claimed.

It will be quite readily understood by those skilled in the art to which this belongs, that this device is susceptible to dif-

ferent structural formations without departing from the spirit or scope of the invention, but a preferred and thoroughly practical embodiment of the same is shown in the accompanying drawings in which—

Figure 1 is a plan view of the front portion of an automobile having my improved pivotal headlight installed thereon. Fig. 2 is a front elevation of the parts shown in Fig. 1, and clearly illustrates the independent feature of the lamp brackets, as well as the means by which they are both operated. Fig. 3 is a side elevation of the parts shown in Fig. 2, showing only the lamp bracket to the left in Fig. 2. Fig. 4 is a sectional view taken on the line 4—4 of Fig. 2, and fully illustrates the abutment bracket stop attached to the frame of the car. Fig. 5 is a detail view of one of the pivotal lamp brackets which support the head light.

Similar reference numerals refer to similar parts throughout the drawings.

In carrying out this invention no change is contemplated in the usual headlamps, the steering gear of the car or the location of the lamps on the car, nor do I prefer to add extra parts to the car, other than those absolutely necessary for proper functioning of the mechanism and to this end I position the usual headlight bracket, designated by the numeral 10 in its bearing 85 socket 11 which is rigidly attached to the car frame 12 or similar rigid position. The bracket 10 is provided at its lower end with a socket member 14, which preferably 90 engages the square portion 15 of the bracket 10 and carries an arm 16 positioned at right angles to the lamp bracket and having the free end 17 bent back in alinement with the car body as clearly shown in Fig. 1 of the drawings. The bracket 10 is further provided with a collar 18 formed integral with the body 19. Immediately below the collar 18 there is formed a cylindrical bearing portion 20 which is adapted to rotatably fit in the socket 11. Immediately below the bearing socket 11 there is positioned a clamping collar 21 which performs the function of holding the bracket in the socket such that any tendency to rattle is entirely eliminated. In order that the 100 bracket 10 be normally held such that the rays of light are projected ahead of the car, parallel to the body thereof, a helical

spring 22 is provided one end of which is rigidly secured to the bearing socket 11 while the other is secured to the bracket, and any effort to turn the lamp is thus resisted by the spring.

A cross bar 23 of the steering gear 24 is provided with upstanding lamp bracket engaging arms 25, each of which is provided with a T-headed abutment or angle 10 portion 26, a necessary provision due to the variable heights of the car body by virtue of the springs 27. Normally the T-head 26 does not engage the lamp bracket extension, and is designed only to engage when 15 the wheels are turned.

For the purpose of keeping the lamp in proper alignment with reference to the car, I have provided a stop 28 adapted to engage a cam shaped abutment 29 on the 20 collar 18 and it will be further obvious that one lamp is affected at a time while the other remains rigid with reference to the car.

From the foregoing it will be obvious 25 that the movement of the headlight is entirely dependent upon the action of the steering gear, and further it will be observed that when the car is driven straight ahead, the lamps both throw their rays directly 30 ahead of the car, unaffected by the varying motions of the car.

Without further description and elaboration it is thought that the many advantages of the herein described headlight operating mechanism will be readily apparent and 35

What I claim and desire to be secured by Letters Patent is—

1. A head light operating mechanism including in combination with the car body 40 and the steering gear, a stationary bracket support, an oscillating bracket element for the head light having a shank portion journaled in and extending below said support, a return spring mounted on the lower end 45 of said shank and engaging therewith, an angled member carried by the said shank, an upstanding T-headed engaging bracket adapted to be clamped to a steering gear element and arranged to engage the angled 50 extension of the lamp bracket.

2. A head light operating mechanism including in combination with the car body and the steering gear, a stationary bracket support carried by the car body, an oscillating bracket element for the head light having a bearing in said support, a socket member detachably fitted to the lower end 55 of said bracket element, a return spring mounted on the lower end of said oscillating bracket and engaging therewith, a rearwardly disposed arm carried by the socket member, and an upstanding T-headed operating member adapted to be clamped to a steering gear element to engage the rearward extension on the socket. 60

In testimony whereof I affix my signature in presence of two witnesses.

HENRY W. BOLLINGER.
